Atty.

UNITED STATES PATENT OFFICE.

JOHN B. ALBRIGHT, OF ROCKFORD, ILLINOIS.

CONTAINER AND HOLDER FOR SHAVING STICKS.

1,415,621.

Specification of Letters Patent. Patented May 9, 1922.

Application filed July 18, 1919. Serial No. 311,831.

To all whom it may concern:

Be it known that I, JOHN B. ALBRIGHT, a citizen of the United States, residing at Rockford, in the county of Winnebago and State of Illinois, have invented certain new and useful Improvements in Containers and Holders for Shaving Sticks, of which the following is a specification.

This invention pertains in general to containers and holders for sticks of plastic material, such for example as sticks of shaving soap.

The primary object of the invention is to provide a shaving stick holder and container of novel construction with the view to obtaining greater economies as regards consumption of the soap. That is, to say, I have provided novel means permitting removal of the shaving stick stub from its holder after the stick has been used down to the holder, so that a fresh stick may be inserted into the holder and the stub attached to the end of the fresh stick, thus avoiding waste and enabling complete consumption of the soap.

I have also aimed to provide a shaving stick holder of the character described, which shall be constructed in such simple manner as to be capable of production at a comparatively low cost and shall embody such characteristics as to render the holder thoroughly practical and serviceable.

In furtherance of these general objects, my invention contemplates, primarily, the provision of a bayonet joint between a shaving stick and its holder, whereby the shaving stick is removably held in the holder in a very satisfactory and effective manner to the ends desired. I have also designed to provide a spring-pressed abutment, against the pressure of which the stick is inserted into the holder socket and thus firmly and securely held in connection therewith by reason of the bayonet joint above mentioned, and which spring serves to eject the shaving stick from the socket after the stick has been given a partial rotative movement, as will be apparent hereinafter.

Other objects and attendant advantages appurtenant to the construction of the holder proper and the several co-operating parts will be appreciated as the invention becomes better understood by reference to the

following description when considered in connection with the accompanying drawings, 55 in which—

Figure 1 is a side elevation of a holder, stick and covering shell embodying my improvements;

Fig. 2, a longitudinal sectional view 60 through said parts in assembled relation;

Fig. 3, a cross-sectional view taken substantially on the line 3—3 of Fig. 2; and

Fig. 4, a side view of the lower end of the shaving stick taken at right angles from 65 the view of the stick in Fig. 1.

The principal parts embodied in my invention are a holder proper 6, a shaving stick 7 and a casing shell 8 all designated generally. The holder is preferably formed 70 in two parts, viz: a base member 9 and a socket member 11. It will be observed that the base member is simply of tubular shape and that the upper edge of its annular wall is turned outwardly at 12 to provide a seat 75 for the marginal flange 13 of the socket member and is then turned inwardly over said flange to thereby rigidly secure the socket member to the base member. The socket member is preferably shaped to provide an inner cylindrical wall or stick receiving socket 14 and an outer annular wall 15 terminating in the marginal flange 13 above mentioned. It will be observed that the tubular socket part 14 extends substantially above the top of the base part and is turned downwardly providing an outer wall 16 which terminates in said marginal flange 13. The casing shell 8 fits snugly over the wall 16 and against the flanged edge 12 of 90 the holder. The casing shell may be of any suitable construction and has a lining of impervious paper or any suitable material to protect the soap. While I have illustrated and described in detail the preferred embodiment of the holder proper, it should be understood that the principal features of my invention are in no way limited to this particular construction, since the invention contemplates broadly the use of the holder 100 proper constructed in any suitable manner but including a stick receiving socket embodying characteristics which will now be described.

I have aimed to provide a novel means 105 for removably holding the shaving stick 7

in the socket in the holder member and to this end have employed a joint or connection which I have termed and is known as a bayonet joint. By means of a joint of this kind 5 a shaving stick may be quickly and easily inserted into and retained in the holder socket, and after the stick has been used down to the holder member the stub may be conveniently removed and used at the end of a 10 fresh stick instead of being wasted as is the case in certain constructions when the stub is permanently held in the holder. Viewing Figs. 1 and 4, it will be observed that I have shaped the shaving stick on diametrically 15 opposite sides to provide L-shaped or bayonet recesses 17, each of which comprises a portion 18 extending longitudinally of the stick and open at the bottom end thereof and a lateral or transverse portion 19 extending 20 partly around the periphery of the stick. The recessed portions 18 are each of a width and depth corresponding to similar dimensions of segmental bosses 21 which are pressed inwardly from the socket wall 11 25 of the holder member and are of greater length than width and arranged in a plane transverse to that of the socket as shown plainly in Figs. 2 and 3. Thus, when the shaving stick is inserted into the holder 30 socket, the bosses or lugs 21 will be received into the recess portions 18, and by giving the stick a partial rotative movement in a clockwise direction, according to the shape of the bayonet joint illustrated, the bosses 35 will be brought into the lateral recesses 19 and confined between the opposed edges 22 thereof. In order to give permanency to the shape of the bayonet recess, I have wrapped the lower portion of the stick with 40 a protective foil 26 or the equivalent, shown in Figs. 1 and 2, which conforms to the shape of said recesses and prevents the bosses 21 from coming in contact with the soap. These edges 22 might be tapered as shown in Fig. 45 to compressingly engage the bosses 21, to thus prevent accidental displacement of the shaving stick from this position, although as will be presently seen I have provided additional means for holding the shaving 50 stick in the socket. This means is in the form of a spring-pressed abutment 23 constantly urged upwardly by a suitable expanding spring 24. It will be manifest that by reason of the upward pressure on the 55 shaving stick when in operative position, the stick will be effectively held against rotative movement in the socket. I have also contemplated forming the lower wall 22 of the recesses in the stick to provide a locking 60 depression 25 indicated by dotted lines in Fig. 4, into which the bosses 21 will be urged by the spring, thus positively preventing accidental displacement of the stick. Such locking effect, however, is not essential, as 65 I find that by reason of the plastic composi-

tion of the stick and its foil facing, the bosses 21 will have considerable frictional engagement with the recesses in the shaving stick, and under the additional holding influence of the spring pressed abutment the stick will 70 be very substantially secured in the holder.

It will be manifest that when a shaving stick is used down to the holder, the stub may be removed by simply inserting a pen knife or any suitable means into the end of 75 the stub and giving thereto a partial rotative movement sufficient to withdraw the bosses 21 from the recesses 19, whereupon the spring 24 will eject the stub from the holder socket. A fresh shaving stick may now be 80 inserted into the socket and secured therein against the spring pressure, and it will be noted that fresh sticks are of such length as to allow sufficient distance between the outer end of the stick and the end wall of the cov- 85 ering shell to permit placement of the stub on the end of the shaving stick. The stub may be easily attached to the shaving stick by simply moistening one or the other and pressing them together sufficiently to establish a holding connection by adhesion of the two soap bodies. Thus, the user obtains the full benefit of every particle of soap in a 90 shaving stick as distinguished from those cases in which a portion of the shaving stick 95 is permanently secured or embedded in the holder and thus wasted. Furthermore, by selling the fresh shaving sticks independent of a holder it is possible for the consumer to purchase these re-fill sticks at a lower 100 price than if it were necessary to purchase the complete holder and stick.

It is believed that the foregoing conveys a clear understanding of the objects prefaced above, and while I have illustrated but a 105 single working embodiment thereof, it should be understood that various changes might be made in the construction and arrangement without departing from the spirit and scope of the invention as expressed in 110 the appended claims, in which—

I claim:

1. A holder for shaving sticks, comprising a holder element composed of a base member and a socket member, the face member having an outer tubular wall, the socket member having an inner tubular wall spaced inwardly from said outer wall, reaching above the latter and turned downwardly and fastened to the upper portion of said outer 120 wall, the tubular wall of the socket member having an inwardly extending boss of greater length than width and arranged in a plane transverse to the axis of the socket, a shaving stick having a bayonet shaped recess for the reception of said boss, and a cover casing adapted to inclose the shaving stick and detachably connect to the holder 125 element.

2. A holder for shaving sticks, comprising 130

a holder element having an inner and an outer tubular wall, the inner wall constituting a socket for the reception of a shaving stick and pressed inwardly to provide a segmental boss of greater length than width and arranged in a plane transverse to the axis of said socket, a shaving stick of plastic material having peripherally formed at one end a bayonet shaped recess adapted to receive said boss upon insertion of the stick into said socket, a protective covering over said end of the stick and conforming to the recesses therein, and a cover casing adapted to inclose the outer end of the shaving stick and to detachably engage the outer wall of the holder element.

3. A holder for shaving sticks, comprising a holder element having an inner and an outer tubular wall, the inner wall constituting a socket for the reception of a shaving stick and pressed inwardly to provide a segmental boss of greater length than width and arranged in a plane transverse to the axis of said socket, a shaving stick having peripherally formed at one end a bayonet shaped recess adapted to receive said boss upon insertion of the stick into said socket, a cover casing adapted to inclose the outer end of the shaving stick and to detachably engage the outer wall of the holder element, and a spring operable between the holder element and the inner end of the shaving stick for urging the same outwardly to prevent displacement of the stick when in operative position and to assist in the removal of the stick when it has been partially rotated for alignment of its longitudinal recess with the boss.

4. A holder for shaving sticks, comprising a holder element having a socket for the reception of a shaving stick, the walls of said socket being shaped to provide a pair of inwardly extending segmental bosses of substantially greater length than width and ar-

ranged in a plane transverse to the axis of said socket, a shaving stick peripherally formed at one end with a pair of bayonet shaped recesses adapted for the reception of said bosses when the stick is inserted into the socket, a protective foil covering the lower end of the shaving stick and covering and conforming to the shape of the bayonet recesses therein, whereby to give permanency to the shape of said recesses and to facilitate removal of the shaving stick from operative connection with said recesses.

5. A holder for shaving sticks, comprising a holder element having a socket for the reception of a shaving stick, the socket wall formed with a plurality of inwardly extending segmental bosses of greater length than width and arranged in a plane transverse to the axis of the socket, a shaving stick of plastic material, the socket end of which is shaped peripherally to provide bayonet recesses adapted to receive said segmental bosses and to compressingly engage the same when in operative position and permit removal of the shaving stick stub at will, and a protective facing interposed between said bosses and recesses and conforming to the shape thereof.

6. A holder for shaving sticks comprising in combination with a shaving stick of plastic material, a holder having a socket for the reception of one end of the stick, said socket having inwardly extending diametrically opposed bosses of substantially greater length than width, said end of the stick being preferably shaped to provide bayonet recesses for the reception of said bosses by longitudinal and rotative movement of the stick in inserting said end into operative position in said socket, and a protective facing for said inserted end of the stick covering and conforming to the shape of said recesses.

JOHN B. ALBRIGHT.
